UNITED STATES PATENT OFFICE.

WILLIAM H. FORSYTH, OF CHICAGO, ILLINOIS, ASSIGNOR TO THE CURTAIN SUPPLY COMPANY, OF CHICAGO, ILLINOIS, A CORPORATION OF ILLINOIS.

AUTOMATICALLY-OPENING CAR-DIAPHRAGM.

1,078,781.

Specification of Letters Patent.

Patented Nov. 18, 1913.

Application filed March 20, 1913. Serial No. 755,573.

To all whom it may concern:

Be it known that I, WILLIAM H. FORSYTH, a citizen of the United States, residing at Chicago, in the county of Cook and State 5 of Illinois, have invented certain new and useful Improvements in Automatically-Opening Car-Diaphragms, of which the following is a specification.

In many styles of railway cars it is customary to use extensible diaphragms which are collapsible and accordion-shaped. It is often desirable or necessary to tilt the outer face plate to which the diaphragm is attached in order to obtain access to the buffer mechanism of the car. Heretofore, considerable difficulty has been experienced in thus tilting the face plate on account of the fact that when this operation is performed the plaits of the diaphragm are very apt to 20 become torn.

In the co-pending application of Stanley W. Midgley, Serial No. 691,347, filed April 17, 1912, a diaphragm is described in which many of the faults of the prior construction 25 have been overcome, since provision is there made for having at least one of the plaits in each leg of the diaphragm composed of two separate pieces of fabric, which are attached to each other by means of studs, in 30 the ends of which are placed cotter pins. The disadvantage of this construction is that if, through carelessness, a workman neglects to remove the cotter pins before the outer face plate is tilted, the diaphragm is subjected to considerable pressure and is apt to 35 become torn or otherwise injured.

In an improved construction covered by Patent #1,056,407 granted to me March 18, 1913, I provide at least one of the plaits in 40 each leg of the diaphragm with a slit which extends to the bottom of the diaphragm. The edges of these slits are connected by fastening devices, which are automatically released when the outer face plate is tilted, and one edge of the slit is thereby forcibly 45 pulled from the other edge. In this way it is impossible for the diaphragm to become torn or injured through the negligence of a workman. By the present invention, I provide not only for the automatic release of 50 the parts, but also against the accidental separation of the edges of the slits by reason of relative movement of the diaphragm plait due to swaying or jolting of the cars, 55 or to buffing and draft strains. These and

other advantages of my invention will be more readily understood by reference to the accompanying drawings, which represent a preferred embodiment of my improvements, and in which,

60

Figure 1 is a longitudinal vertical section through the end portion of a car. Fig. 2 is a transverse vertical section taken on the line 2—2 of Fig. 1. Fig. 3 is an enlarged horizontal cross section on the line 3—3 of Fig. 2. Fig. 4 is an enlarged horizontal section showing the construction of one of the fastening devices; and Fig. 5 is a section on the line 5—5 of Fig. 4.

65

To one face of the end wall or post 10 of the car is fastened, by means of a metallic strip 11, one end of an inverted U-shaped accordion diaphragm composed of a plurality of inverted U-shaped strips of fabric 12 which are fastened together along their longitudinal edges in any suitable manner, as, for example, by the binding strips 13. Near the center of the diaphragm, one of the plaits thereof is allowed to remain open at its lower portion, thereby forming the slit 14 between the edges of the fabric 12. To the edges of the fabric adjacent to the slit 14 are attached a plurality of fastening devices represented as a whole by 15.

70

Any suitable type of fastening device the parts of which become separated only on the application of a pull exerted on one certain edge of one part in a direction away from the opposite part may be used in connection with my device, but one preferred type of fastening device is illustrated in Figs. 4 and 5. This fastening device comprises two members, one a shaft 16 having a head 17 and a stud 18 presenting the flat shoulder 19. Engaging the short shaft or shank 16 are the washers 20 which engage opposite surfaces of the fabric 12. The material 12 on the opposite side of the slit 14 is clamped between the parts 21 and 22 of the other two-part fastening member which is adapted for coöperation with the stud 18. The part 22 is in the nature of a head secured to the neck 23 of the part 21, the part 21 is shell like and has in the wall 24 an opening 25 adapted to pass the stud 18 and within the shell about the margin is arranged a spring 26 the ends of which extend in substantially parallel relation across the opposite sides of the opening 25 and are then deflected toward each other so as to present substantially a

U-configuration and adapted to engage beneath the shoulder 19 on three sides of the shank 16. If tilting pressure be applied beneath that side of the shell 21 corresponding to the open end of the U the stud 18 readily separates from the shell 21 the reaches of the spring riding up on the periphery of the stud but if the shell be tilted from that side corresponding to the closed end of the U, 10 the deflected ends of the spring engage beneath the shoulder 19 and the device is locked against separation, and likewise if the shell be tilted from either side of the U, separation being effected only when tilted at 15 the open end of the U.

To the front end of the diaphragm is attached an outer face plate 27 of the usual and well known construction, the end of this face plate coöperating with the buffer 20 mechanism of the car represented generally at 28.

When it is desired to tilt the outer face plate 27 into the position indicated in dotted lines in Fig. 1 so as to obtain access to the buffer mechanism 28, the edges of the fabric 12 on opposite sides of the slit 14 are separated from each other throughout the length of said slit by the tilting of the face plate, the same swinging forwardly and upwardly 30 in a vertical plane. The shells of the fastening devices are attached to the edges of the fabric with the open end of the spring U downward so that in tilting the face plate the stud and shell are separated automatically, whereas they will not separate by reason of any movement of the edges laterally or in a horizontal longitudinal direction. The separation of the fastening devices is, as will be readily understood, a 35 progressive one beginning at the bottom of the slit and releasing each of the fastening devices in turn by a tilting action applied from below and directed forwardly and upwardly, this being the force naturally exerted in swinging the face plate as indicated. When the face plate is returned to its normal position the stud 18 of each fastening device is readily snapped into engagement with the spring 26, the beveled 40 head serving to spread the spring as it enters.

It will be apparent to those skilled in the art that many changes may be made in the detailed construction of the parts which I have described without departing from the spirit or scope of my invention.

I claim:

1. A car vestibule diaphragm, each leg of which includes separable portions, and fastening means for holding together the separable portions of each leg, said fastening means being separable only by force applied

in a direction substantially lengthwise of the leg, substantially as described.

2. A car vestibule diaphragm, each leg of 65 which includes separable portions, and fastening means for holding together the separable portions of each leg, said fastening means being separable only by force applied in a direction upwardly and substantially lengthwise of the slit between the portions, substantially as described.

3. A car vestibule diaphragm, each leg of 75 which includes separable portions, and fastening means for holding together the separable portions of each leg, said fastening means being separable only by force applied upwardly and outwardly in a substantially vertical plane, substantially as described.

4. A car vestibule diaphragm, each leg of 80 which includes separable portions, and fastening means for holding together the separable portions of each leg, said fastening means being separable by force applied in a plane including the slit and not in a 85 plane at right angles thereto, substantially as described.

5. A car vestibule diaphragm for a single car, each leg of which includes portions separable upon a substantially vertical 90 plane, and fastening means for holding together the separable portions of each leg, said fastening means adapted to be automatically released only on tilting of that face plate to which the diaphragm is attached, substantially as described.

6. A car vestibule diaphragm of accordion form, and fastening means for holding together the edges of the material, said fastening means adapted to be automatically 100 released only on tilting of the face plate to which the diaphragm is attached, substantially as described.

7. A car vestibule diaphragm of accordion form having a plait in each leg provided with 105 a slit therein, and coöperating fastening means on the edges of the fabric adjacent to said slit, said fastening means adapted to be automatically released on the application of an outward and upward pull on the 110 fabric on one side only of said slit in a direction away from the fabric on the opposite side of said slit, whereby on tilting the face plate to which said diaphragm is attached to give access to the buffer mechanism 115 said plait is automatically opened and tearing thereof is avoided while jars and lateral stresses are ineffective to open the plait substantially as described.
